UNITED STATES PATENT OFFICE.

CHRISTIAN KOHLHAAS, OF LONG BRANCH, NEW JERSEY.

SHADE HOLDER.

Application filed June 24, 1921, Serial No. 430,041. Renewed May 18, 1922. Serial No. 562,042.

To all whom it may concern:

Be it known that I, CHRISTIAN KOHLHAAS, a citizen of the United States, and a resident of Long Branch, in the county of Monmouth and State of New Jersey, have invented a new and Improved Shade Holder, of which the following is a full, clear, and exact description.

This invention relates to improved light shade holders.

The object of the invention is to provide a light shade holder which may be adjusted to hold the shade at any angle to the light.

Another object is a shade holder which is compact in form and so shaped that it may be easily placed on the lamp chimney or light bulb without exposing the fingers to the heat of the light.

These and other objects will be more clearly understood from the following detailed description and accompanying drawings.

Figure 1 shows the shade and shade holder mounted on a lamp;

Figure 2 is a cross section along the line 2—2, Figure 1;

Figure 3 is a top plan view of the shade holder;

Figure 4 is a cross section along the line 4—4, Figure 3;

Figure 5 shows the shade holder mounted on the cylindrical chimney of a gas lamp.

Referring to the above-mentioned figures, a flexible wire has an arc-shaped portion 10. At the ends 11 and 12 of the arc-shaped portion 10 the wire is bent and brought back approximately parallel to the inside of the arc-shaped portion thus forming an arc-shaped loop 27. Loops 13 and 14 are formed in the portions 15 and 16, which are approximately parallel to the arc-shaped portion 10. The portions 15 and 16 overlap for a short distance and are then bent so that they project radially inward, forming members 17 and 18. Each of these members 17 and 18 are bent to form semi-circular parts 20 and 19, which cross near their junction with the members 17 and 18. At the outer ends of the semi-circular shaped members 19 and 20 the wire is bent to form horns or arc-shaped portions 21 and 22 which serve as guides when the shade holder is being forced onto a lamp chimney or electric light bulb.

Springs 24 are fitted into the loops 13 and 14. These springs are made of any flexible

material and the bottom portion may be made of a variety of shapes. The upper end is hook-shaped having a part 25 extending approximately parallel to the upper part of the main portion. A depression 26 is made in the part 25. This depression serves to fit over the wire forming the loop to hold the clip in the loop.

The shade 23 is fitted through the arc-shaped loop 27 and is held at an angle to the light by the clips 24. The angle at which the shade is held may be varied by bending the clips 24. This shade 23 may be made of a variety of material, the simplest, cheapest and most satisfactory of which is light cardboard.

When it is desired to place the shade holder in position the horns 21 and 22 are placed against the lamp chimney 25 and a slight force applied which causes the hook members which are made of the portions 17, 20, 22 and 18, 19, 21 to open and fit around the chimney, as shown in Figure 2. When it is desired to remove the shade holder a slight pull is exerted and the hook members are spread apart and slide off the chimney.

The shade holder is shown in combination with an ordinary oil lamp chimney, but it may be used with the chimney of a gas lamp and with an electric light bulb.

The chimney of a gas lamp is cylindrical in shape and does not present any curved sides to support the holder. The gripping qualities of this holder, due to its construction, retains it in any desired position on cylindrical chimneys. The holder may be moved up or down on such a chimney and it will remain in the position to which it is moved. The shade, which may be made of any shape, will be held at any angle depending on how the clips 24 are bent.

Various forms of wire shade holders for oil and gas lamps and electric light bulbs have been made. Many of those that depend upon the spring in the shade holder arms to hold them in position are unsatisfactory on account of the hook arms becoming strained. This device is constructed of such a shape that the hook arms retain their resiliency.

I claim:

1. A lamp shade holder comprising, an arc-shaped loop formed by folding wire, a plurality of loops formed in the inside of the arc, a plurality of clips mounted in the

loops, and a pair of hooks formed from the ends of the wire and extending radially inward.

2. In combination with a light shade, a light shade holder comprising, an arc-shaped loop into which the shade fits, a plurality of spring-holding loops, a plurality of springs mounted in the loops, and a pair of spring hooks for engaging the lamp chimney or bulb.

3. A lamp shade holder comprising, an arc-shaped loop formed by bending a portion of a flexible wire to an arc shape and folding the ends back along the inner side of the arc-shaped portion, a plurality of spring-holding loops in the inner overlapping portions of the wire, a plurality of springs mounted in the loops, and a pair of hooks formed from the ends of the overlapping wires, by allowing them to overlap for

a short distance, then bending them radially inward and forming semicircles in the wire which cross near their junction with the radial portions and forming at the end of the semicircular parts two arc-shaped portions which curve outward to form a guide.

25

4. In combination with a light shade, a light shade holder comprising, an arc-shaped loop for carrying the shade, a plurality of spring-holding loops in the inner wall of the arc-shaped loop, a plurality of flexible springs mounted in the loops and serving to hold the shade at any angle to the light, and semicircular hooks integral with the inner wall of the arc-shaped loop and extending radially inward, crossing near the outer ends of the semicircular portions and having arc-shaped guides on the inner ends.
